UNITED STATES PATENT OFFICE

136,827

DESIGN FOR A COMBINED RADIO RECEIVER AND CLOCK CASING

Robert David Budlong, Skokie, Ill., assignor to
Zenith Radio Corporation, Chicago, Ill., a cor-
poration of Illinois

Application September 3, 1943, Serial No. 111,063

Term of patent 14 years

To all whom it may concern:

Be it known that I, Robert D. Budlong, a citizen of the United States, residing at Skokie, in the county of Cook and State of Illinois, have invented a new, original, and ornamental Design for a Combined Radio Receiver and Clock Casing, of which the following is a specification, reference being had to the accompanying drawing, forming a part thereof.

Figure 1 is a front elevational view of a com-

bined radio receiver and clock casing, showing my new design;

Figure 2 is a side elevational view of the same; and

Figure 3 is a bottom view thereof.

I claim:

The ornamental design for a combined radio receiver and clock casing, as shown.

ROBERT DAVID BUDLONG.
